UNITED STATES PATENT OFFICE.

ZACHARY T. FRENCH AND WILLIAM C. MEYER, OF BOSTON, MASSACHUSETTS.

WELT-BEATING MACHINE.

SPECIFICATION forming part of Letters Patent No. 598,727, dated February 8, 1898.

Application filed April 28, 1896. Serial No. 589,369. (No model.)

To all whom it may concern:

Be it known that we, ZACHARY T. FRENCH and WILLIAM C. MEYER, of Boston, county of Suffolk, State of Massachusetts, have invented an Improvement in Welt-Beating Machines, of which the following description, in connection with the accompanying drawings, is a specification, like letters on the drawings representing like parts.

10 This invention has for its object to improve the construction of machines for beating out welts of welted boots and shoes; and it consists, essentially, in the combination of a welt-beating hammer, means for operating it, a 15 table upon which the welt is placed, a movable support therefor, a movable abutment against which said support continuously rests and which acts to resist the blows of the hammer, a treadle, and a treadle-rod connecting said treadle with said movable abutment.

The movable abutment is constructed and arranged to serve as an adjusting device by which the position of the table relative to the 25 hammer may be varied, and as preferably constructed the said abutment has bearings which are at all times directly in the line of thrust of the table-support. As herein shown, the table-support is pivoted to the frame, and 30 the abutment is likewise pivoted to the frame, the latter consisting, essentially, of a cam of varying radius, so that as it is turned on its pivot it will vary the position of the table-support which rests upon it.

35 Figure 1 shows in side elevation a welt-beating machine embodying this invention; Fig. 2, an end view of the machine, the welt-beating hammer and welt-support or table being omitted; and Fig. 3, a plan view of the 40 welt-support or table.

The welt-beating hammer *a* is secured to the lower end of a rod or bar *a'*, having its bearings in projecting portions *a²* *a²* of the main framework *A*, said rod or bar *a'* being 45 movable vertically in its bearings. A sleeve *b* is placed upon or embraces the rod or bar *a'* at a point more or less midway its length, it having a laterally-projecting stud *b'*, and a main rotating shaft *c*, having its bearings 50 in the main frame *A*, has secured to it suit-

able driving-pulleys at one end and has projecting from its opposite end a crank-pin *c'*, and a link *b²* connects said crank-pin *c'* with the laterally-projecting stud *b'* on the sleeve *b*, so that as the shaft *c* is rotated the sleeve 55 *b* will be reciprocated.

In order that the reciprocating sleeve may impart a corresponding movement to the rod or bar *a'*, we have secured to said rod or bar at a point just above the sleeve *b* a collar *d*, 60 against the lower end of which said sleeve *b* bears, and a strong spiral spring *d'* encircles said rod or bar *a'*, the upper end of which bears upon or against the sleeve *b* and the lower end of which bears upon or against adjusting-nuts *d²*, turned on a threaded portion of said rod or bar. As the shaft *c* rotates the sleeve *b*, acting upon the spring *d'*, depresses the welt-beating hammer, and then 65 acting upon the fixed collar *d* raises said welt-beating hammer. 70

By connecting the rod or bar *a'* with the means for operating it by means of the loose sleeve *b*, fixed collar *d*, spring *d'*, and adjusting-nuts *d²* it will be seen that an adjustable yielding connection is provided whereby 75 the welt-beating hammer will deliver a succession of yielding blows.

e represents the table upon which the welt to be beaten out rests, and it is herein shown 80 as having a tapering lip adapted to enter the crease or inseam or bear against the last at the face side of the welt.

The table *e* is placed upon or held by a support *e'*, pivoted at *e²* to the main framework. 85 The table-support *e'* is formed with a recess for the table *e*, the top of the recess being provided with a tongue and the top of the inner end portion of the table being provided with a groove to receive said tongue, and a 90 set-screw *e³* is provided, which may be used to hold the table *e* fixed in any desired adjusted position, or the table *e* may be made movable in and out for a short distance, if desired, in which case the set-screw *e³* will 95 be loosened or omitted and a spring *n* (see dotted lines, Fig. 1) will be provided, bearing against a pin *n'* on the table-support *e'* and against the table *e*, the action of which is to move the table out, and pins *n²* pass up 100

through webs or projections on the table-support and enter slots or grooves formed in the under side of the table, said slots or grooves being of such length as to limit the forward movement of the table, its rearward movement being limited by the inner end of the table bottoming in the recess. The table *e*, thus yieldingly supported, may be moved in and out in order that the welt-beating hammer may act upon the welt more or less distant from the edge.

It is obvious that the table *e* may be made integral with the support *e'*; but by making it separate it may be adjusted in and out or caused to yield.

The pivoted table-support *e'* rests upon or against a cam *f*, which serves as an abutment for it, and said cam *f* is pivoted to the frame at *f'*. The cam *f'*, which thus serves as an abutment for the table, has its curved surface made of gradually-increasing radius from end to end, so that when the cam is in one position, as represented by dotted lines, Fig. 1, its point of shortest radius is in contact or engagement with the table-support, and consequently the table *e* is more or less removed from its normal elevated position, and when the cam *f* is moved into its opposite extreme position, as represented by full lines, Fig. 1, its point of longest radius is in contact or engagement with the table-support, and as a consequence the table *e* is held in its most elevated position. By holding the cam *f* at different intermediate points or positions the normal elevated position of the table *e* may be varied.

As a simple way of limiting the movement of the cam *f* in one direction—*i. e.*, in a direction to raise the table *e*—an adjusting-screw *f*² passes through a projection *f*³ on the cam and is adapted to strike against a fixed point or stop *f*⁴ on the frame. The cam has attached to it a treadle rod or chain *g*, which may be connected with any suitable treadle for the purpose of depressing it or moving it in a direction to lift the table, and a strong spring *g'* is attached at one end to the cam *f* and at the other end to the table-support, which acts to move the cam *f* in the opposite direction.

This construction of adjusting and operating device for adjusting and operating the table *e* may be changed in many ways without departing from the spirit and scope of the invention, but the particular construction shown—viz., the cam *f*—enables the table to be adjusted and held in different planes or elevations and also to be freely moved to facilitate admitting the work and also provides a good and efficient abutment to oppose or resist the force of the welt-beating hammer.

The table-support *e'* has a tendency to turn on its pivot when its table *e* is receiving upon it the repeated blows of the hammer, and said support bears against the cam *f* continuously, the thrust being in a direction toward the pivots or bearings *f'* of said cam, such direc-

tion of thrust continuing notwithstanding movements of the cam *f* to vary the position of the table.

The front end of the table is made as a stationary nose; but it is obvious that a loose roll may be provided without departing from the spirit and scope of the invention.

We claim—

1. In a welt-beating machine, the combination of a welt-beating hammer, a table upon which the welt is placed, a movable support therefor, a movable abutment against or upon which said table-support continuously rests, bearings for said abutment which are at all times in the line of thrust of the table-support, means for moving said abutment to lower the table for the introduction of the work, and a treadle connected with said abutment for moving it to raise said table to different elevations, substantially as described.

2. In a welt-beating machine, the combination of a welt-beating hammer, a table adapted to receive upon it the welt, a support for said table, means for adjusting its position relative to the hammer consisting of a movable abutment against which said table-support rests, means for continuously holding said table-support in engagement with said abutment, bearings for said abutment which are at all times in the line of thrust of the table-support, and means for moving said abutment, substantially as described.

3. In a welt-beating machine, the combination of a welt-beating hammer, a table upon which the welt is placed, a pivoted support for said table, a movable abutment for said pivoted table-support, which resists the blow of the hammer, and means for moving said abutment, substantially as described.

4. In a welt-beating machine, the combination of a welt-beating hammer, a table upon which the welt is placed, a movable support therefor, and a pivoted cam *f* of varying radius which serves as an abutment for said table-support and as a means for moving it, substantially as described.

5. In a welt-beating machine, the combination of a welt-beating hammer, a table upon which the welt is placed, a pivoted support therefor, and a pivoted cam of varying radius against which said table-support abuts, which resists the blow of the hammer, substantially as described.

6. In a welt-beating machine, the combination of a welt-beating hammer, a table upon which the welt is placed, a movable support therefor, and a pivoted cam *f* of varying radius which serves as an abutment for said table-support and as a means of moving it, and an adjustable limiting-stop for said cam, substantially as described.

7. In a welt-beating machine, the combination of a welt-beating hammer, a table upon which the welt is placed, a pivoted support therefor, and a pivoted cam of varying radius against which said table-support abuts, which resists the blow of the hammer, and a spring

connecting said cam with said table-support, substantially as described.

8. In a welt-beating machine, the combination of a welt-beating hammer, a table upon which the welt is placed, a movable support therefor and a yielding device for said table permitting it to move laterally relative to the hammer and a movable abutment for said table-support which resists the blow of the hammer, substantially as described.

9. In a welt-beating machine, the combination of a welt-beating hammer, means for operating it, a table upon which the welt is placed, a movable support therefor, a mov-

able abutment against which said support continuously rests and which acts to resist the blows of the hammer, a treadle, and treadle-rod connecting said treadle with said movable abutment, substantially as described.

In testimony whereof we have signed our names to this specification in the presence of two subscribing witnesses.
